UNITED STATES PATENT OFFICE

2,456,189

CONTINUOUS SEDIMENT SEPARATOR

Benjamin F. Harbison, Rocky Ford, Colo.

Application July 7, 1945, Serial No. 603,713

2 Claims. (Cl. 209—424)

1

This invention relates to a sugar beet sediment collector, that is, a device for removing rocks, sand, clods and trash from the flume floating sugar beets to a sugar factory and has for its principal object the provision of a device of this character which will be continuous in its operation so that it will not require shutting down for cleaning purposes and yet which will quickly and completely remove all of the above foreign materials from the flume stream without loss of beets.

A further object is to so construct the device that it can be inserted in the present beet flumes without disturbing the latter.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing.

Fig. 1 is a longitudinal section through the improved continuous sediment collector;

Fig. 2 is a fragmentary detail plan view of a portion of the bottom of the beet channel of the device;

Fig. 3 is a cross section therethrough, taken on the line 3—3, Fig. 1; and

Fig. 4 is a fragmentary end view of the upper portion of the collector.

A typical beet conveying flume is indicated at 10. The invention is designed for installation in the flume 10 at any convenient point therealong.

The device employs a basin 11, formed of concrete or other suitable material, which acts as an enlargement of the flume 10 and which is filled with water from the flume and maintains the water level thereof. An open ended drum 12 of wood, sheet metal or other material, is mounted in the basin 11 so as to extend below the water line and closely adjacent the bottom of the basin. The drum 12 is rotatably supported in any desired manner. Preferably, it is provided with an internal track ring 14 at each extremity. Each of the track rings 14 rides on three internally positioned, flanged, supporting rollers 13, the uppermost rollers supporting the weight of the drum and the side rollers acting to prevent side swing thereof. The rollers 13 are mounted on the extremities of roller shafts 24 mounted in conventional bearings 31.

Each of the roller shafts 24 is secured to a drive pinion 16 which is mounted on a drive shaft 32. The drive shaft 32 is supported in bearings 17 and is driven from any suitable source. The drum 12 is rotated through the medium of ring gears 15, there being one ring gear secured on each extremity of the drum. The ring gears are driven from drive pinions 16 mounted on a drive shaft 32 alongside of the drum. The drive shaft is carried in any suitable bearings 17 and is driven from any suitable source.

The interior of the drum 12 carries a plurality of parallel, spaced, longitudinally-extending pockets 18 positioned to carry material upwardly on the ascending side of the drum and discharge it at the top thereof.

The discharged material falls into an elongated hopper 19 which directs it upon an endless conveyor belt 20 extending longitudinally of the interior of the drum 12.

The conveyor belt discharges the material to any suitable receiver such as a second conveyor belt 21 which carries it to waste.

A flow channel is outlined across the basin 11, between the two extremities of the flume 10, by means of two side walls, each formed of louver-like side slats 22. The side walls act as continuations of the side walls of the flume and act to guide the incoming beets across the basin 11 to the continuation of the flume 10 on the far side thereof.

Two parallel supporting beams 33 extend across the basin 11 below the slats 22. A plurality of adjustable grids 23 are mounted between the

beams 33 and form the bottom of the channel across the basin. The grids consist of a plurality of separated bars which allow sand and gravel to pass therethrough. Each grid is mounted at one end on a crank shaft 25. Each of the crank

shafts 25 terminates in a crank arm 36 which are connected together, by means of a longitudinally extending connecting rod 26. A notched adjusting bar 27 is connected to the rod 26 by means of which the angle or incline of the

grids is manually adjusted and set.

A water jet pipe 28 extends across the channel immediately inside of the entrance of the flume 10. This pipe contains a longitudinally extend-

ing slot to direct a sheet or jet of water there-

from. The pipe 28 may be rotated by means of

a lever 29 and an adjusting rack bar 34 so that

the direction of the jet of water discharging

therefrom may be varied and adjusted. Water

is fed to the jet pipe by means of a pressure

supply pipe 30 from any suitable pumping source.

In use, the drum is continually rotated and

the beets together with the usual foreign ma-

terials, such as rocks, sand, gravel, mud, etc.,

are carried to the basin 11 by means of the water

in the flume 10. The beets are guided by the

slats 22 across the basin 11 and return at the opposite side of the basin to the flume 10.

The upward sheet or jet of water from the jet pipe washes the clods and mud loose from the beets and forces the latter toward the surface of the flow. Each of the grids 23 in turn causes a tendency to lift the beets and separate the foreign materials therefrom as they pass along the channel. These materials gravitate downwardly between and through the grids 23 and between the outwardly and downwardly inclined louver-like slats 22 to the bottom of the drum 12. Rotation of the drum gathers the accumulated rocks, sand, soil and other sediment, lifts it in the pockets 18 and dumps it onto the conveyor 20 by means of which it is carried off. The adjusting bars and racks 27 and 34 are adjusted to obtain a maximum separation without clogging or interfering with the flow of the beets.

The upward incline of the gratings allows the smaller sand and gravel to sift directly therethrough. The larger clods, rocks, etc., travel up the gratings and fall over the extremities between the gratings. A plurality of annular baffle plates 35 extend circumferentially about the interior of the drum and divide the pockets 18 into sections. The baffle plates 35 prevent the formation of currents lengthwise of the drum which would result in washing the sediment toward and through one end of the drum.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A sugar beet sediment collector comprising: a water containing basin; an imperforate cylindrical drum mounted to rotate partially submerged in said basin; a beet intake flume entering said basin; a beet discharge flume discharging from said basin, said flumes being in alignment with each other at opposite ends of and in axial alignment with said drum; side walls extending through said drum from the sides of the intake flume to the sides of the discharge flume; spaced apart, laterally extending grid

bars extending between said side walls above the bottom side of said drum to allow foreign materials to settle between said grid bars to said drum; an elongated hopper within said drum below the upper side thereof to receive the foreign materials from the ascending side of said drum; a water jet pipe extending horizontally across the basin end of the intake flume with its jets directed upwardly into the incoming flow.

10 2. A sugar beet sediment collector comprising: a water containing basin; an imperforate cylindrical drum mounted to rotate partially submerged in said basin; a beet intake flume entering said basin; a beet discharge flume discharging from said basin, said flumes being in alignment with each other at opposite ends of and in axial alignment with said drum; side walls extending through said drum from the sides of the intake flume to the sides of the discharge flume; spaced apart, laterally extending grid bars extending between said side walls above the bottom side of said drum to allow foreign materials to settle between said grid bars to said drum; an elongated hopper within said drum below the upper side thereof to receive the foreign materials from the ascending side of said drum; a water jet pipe extending horizontally across the basin end of the intake flume with its jets directed upwardly into the incoming flow, and means for rotating said jet pipe to vary the discharge angle of said jets.
